UNITED STATES PATENT OFFICE.

VINTON E. SISSON, OF CHICAGO, ILLINOIS, ASSIGNOR TO WILLIAM E. WINE, OF TOLEDO, OHIO.

VENTILATOR FOR CARS.

Application filed June 14, 1922. Serial No. 568,363.

To all whom it may concern:

Be it known that I, VINTON E. SISSON, a citizen of the United States, residing at Chicago, in the county of Cook and State of Illinois, have invented certain new and useful Improvements in Ventilators for Cars, of which the following is a specification.

The object of my invention is to provide a ventilator for freight cars, which is of simple construction with a maximum of efficiency. A further object of my invention is to provide an efficient means for locking the ventilator in its open or closed position.

A still further object of my invention is to provide a ventilator for cars which may be embodied in the car without weakening the car structure, particularly the end structure; a still further object of my invention is to utilize parts of the car structure as a reinforcement for the ventilator.

Another object of my invention is to provide a combined car ventilator and "lumber door."

A further object of my invention is to provide a ventilator with means to prevent the unauthorized removal of the ventilator blades.

A further object of my invention is to provide a car ventilator which embodies a maximum of strength, weatherproofing and clearance for air currents; and with these and other objects in view my invention consists of the parts and combination of parts as hereinafter set forth.

In the drawings:

Figure 1 is an end elevation of a box car showing my improved ventilator in position.

Figure 2 is an enlarged detail view of my improved ventilator, the car structure being broken away.

Figure 3 is a transverse sectional view of Figure 2.

Figure 4 is a vertical sectional view of the ventilator with the blades closed in full lines and their open position indicated by dotted lines. Figure 4^a is a side elevation of one of the side members.

Figure 5 is a side elevation of the ventilator, part of the car structure being in section.

Figure 6 is a front elevation of the ventilator frame.

Figure 7 is a front elevation of the combined ventilator and lumber door, the car structure being broken away.

Figure 8 is a front elevation of one of the ventilator blades.

Figure 9 is a vertical sectional view of the same.

Figure 10 is a front elevation of the top member of the ventilator frame.

Figure 11 is a bottom plan view of Figure 10.

Figure 12 is a bottom plan view of the lower member of the ventilator frame.

Figure 13 is a front elevation of the lower member of the ventilator frame.

Figure 14 is an enlarged detail sectional view of the line 14—14, Figure 11.

Figure 15 is an enlarged detail sectional view on the line 15—15, Figure 13.

Figure 16 is an enlarged detail sectional view on the line 16—16, Figure 10.

Figure 17, is an enlarged detail sectional view on the line 17—17, Figure 12.

Figure 18 is a vertical sectional view of the combined ventilator and lumber door attached to a car.

Figure 19 is an enlarged detail sectional view showing the construction of the lower member of the ventilating frame adapted to a wooden car construction.

Figure 20 is a similar view showing the adaptation of the side member to a wooden car construction.

The reference numeral 1 designates the end plates of a car, which for the purpose of illustration are shown to be metal plates having horizontally disposed corrugations 2 pressed therein. These plates are secured to the usual commercial rolled angle bars 3 known as Z bars, which extend from the end sill 4 to the eaves of the car and constitute end braces for the car. These end braces 90 constitute hangers or supports to which I rivet, or otherwise suitably secure the ventilators, as will hereinafter be pointed out.

The frame of the ventilator is composed of four members, (see Fig. 6) the top 5, bottom 6, and sides 7 and 8. The top member 5 is provided with a depending flange 9 at

its outer edge which serves as a water shed or drip to shed the elements and, as will be hereinafter explained in connection with Figure 4, functions with the top vane or 5 blade to form a weatherproof joint with said vane. Extending upwardly from the top member 5 is a flange 10 which is curved to match the curvature of the corrugations of the end sheets. This flange and the body of 10 the top member extend beyond the ends of the hood 9 as will be seen in Figures 10 and 11 and the top member is provided at its inner edge with perforated lugs 11.

The lower member or sill 12 of the 15 ventilator frame has an outwardly inclined face which terminates at its outer edge in an up-turned flange 13 against the outer face of which the lower edge of the lowermost vane contacts and overlaps, as shown in Figure 20 4 to provide a weatherproof joint. The sill is provided with drift or drain openings 14 through which condensation and other moisture may readily pass to the outside of the car. The sill is also provided with 25 perforated screen lugs 15, and with a depending flange 16 curved to fit the corrugations of the end sheets. At each end of the sill is a vertical flange 17 extending, at its base, the 30 width of the sill and provided with a rivet opening 18 to facilitate the connection between the side and sill members.

The side members are similar in construction, therefore but one will be described in detail. The side bar or stile 7 is turned inwardly at its upper end as shown at 19 in 35 Figures 4 and 6, under the top member 5 and riveted thereto and by turning this end under the top member 1 form a weather proof joint between the two members. The 40 lower end of the side member is riveted to the end flange 17 on the outside thereof so that moisture will drip down beyond the joint (see Figure 6).

On the inner face of the side member 1 45 form combined vane stops and weatherproofing ribs 20, 21, 22, and 23. The stop 20 terminates at its upper end under the hood of the top member of the frame and back of the flange 9 thereof, and at its lower 50 end terminates at the outer edge of the side member. It will be noted that the side members are bellied outwardly, as at 24, thereby providing guards against side drafts at the ends of the vanes blowing the 55 elements in the car at the ends of the vanes. It will be noticed that the stops 21 and 22 are alike their upper ends are back of the pivot of the vanes and that immediately under the pivots they are concaved thereby the better 60 to shed moisture outwardly that may enter around the pivots. At the lower portion these stops are deflected rearwardly in adaptation to the formation of the lower edge of the vane and thence extend for-

wardly to the outer edge of the side member. The stop 23 at its lower end overlaps the flange 13 of the sill on the outside as shown in Figure 4. The side members have flanges 37 and 38 which are secured by rivets to the end braces 3.

The blades or vanes 25 are suitably pivoted in the side members 7 and 8 and are of such construction as to curvature that a maximum air passage is formed between them when they are open and as will be seen 75 in Figure 4 when closed overlap substantially one half their width thereby making a weatherproof joint between them. The top edge of the top vane 25, when in its closed position, is housed in the hood and back of 80 the flange 9 of the upper member 5 of the frame thereby providing a weather proof joint; while the lower edge of the lowermost vane overlaps outside the flange 13 of the sill member of the frame thereby making a 85 weatherproof joint at this point.

The vane operating link 26 is secured to the vanes by means of the supports 27.

A cross brace 28 is secured between the side members of the frame and has its upper 90 face inclined toward the outer edge of the frame to readily shed moisture. The ventilating frame is provided at its inner edge with a screen 29 to prevent the entrance of small animals when the vanes are open, also 95 to prevent the unauthorized extraction of goods from the car. This screen is secured to the lugs 15 and 11 of the top and bottom members and similar lugs on the side members and cross brace 28, as shown in Figure 4.

The side member 8 is provided with a vertical slot 30, the top of which, as will be seen in Figure 4, is slightly below the plane of the underface of the middle vane. A lug 31 105 having a substantially right angle base 32 is formed on the outer side face of the side member 8, said base 32 being perforated while a gravity lock 32a is pivotally secured at 33 to the lug 31 and provided with a lock 110 end 34 slightly offset, vertically, from the lock 32, as shown in Figure 5 and adapted to enter the slot 30; the inner face of the lower portion of the lock end 34 being slightly bevelled to adapt it to the outer 115 face of the vanes.

This locking member is provided with a sidewise extension 35 having a perforation and a lock pin 36 is adapted to pass through the perforations of the extensions 31 and 35 120 thereby locking the vanes in open and closed positions. The lock pin is provided with an opening near its lower end to receive a suitable lock. When the vanes are in closed position the lock end 34 rests against the 125 outer face of the middle vane, and when the vanes are in open position the lock end engages the under face of the middle vane,

whereby the vanes are locked in either position. The pin 36 is secured against loss by means of the chain 37.

In Figures 19 and 20 I have shown a slight variation in some of the details adapting the ventilator frame to a wooden car the outside wood sheathing being designated by the reference numeral 38 and the inside sheathing by 39.

10 In Figures 7 and 18 I have illustrated a combined ventilator and lumber door and in this embodiment of my invention the top and side members 40 and 41 and the stops 42 are substantially like similar parts here-
15 tofore described except that the stops 42 are continuous and are so formed that they provide trunnion bearings 43 for the trunnions of the vanes 44. The stops are continued as at 45 to form a bearing for the side edges 20 of the lumber door 46 which is journaled at its top edge in the bearing 47, also formed in the stops. The sill 6 has no flange at its front edge as in the construction here-
25 tofore described, inasmuch as a weather proof joint is formed between the lower edge of the door and the sill by means of a stiffening flange 48 formed on the lower edge of the door which fits under the sill as shown in Figure 18. A gravity bolt 49 is 30 slidably mounted on the inner face of the lumber door and engages a keeper 50 on the sill to lock it in closed position while the vanes may be locked as described in connection with the other figures. A vane stop 35 51 is secured to the side members of the ventilating frame.

Referring to Figures 4 and 4^a it will be observed that the stops at a point substantially opposite the lower edge of each vane has a flattened portion 52, which provides a substantial seat or contact for an edge portion of the flat central portion 53 of the vanes, thereby forming another weather proof joint.

45 It will be noted that the ventilator is supported by and between the end braces whereby said ventilator is protected and materially strengthened by the said end braces, besides which the end braces serve to fend off side drafts, and rain and snow carried by such drafts, from the ventilator, as will be understood from an observation of Figure 3, from which it will be seen that side drafts will be caught under the outwardly projecting flange of the braces 3 and fended off.

60 The edges of the corrugated end sheets are flat in that portion which underlies the bottom flange of the end braces 3 so as to ensure a snug weatherproof joint at this point, and further to provide a flat surface upon which the flanges 37 and 38 of the side members of the ventilator may be secured, as shown in Figure 3.

The stop 51 prevents the unauthorized lifting or removal of the vanes.

Referring to Figure 6 it will be seen that the journal bearings 54 in the side members of the frame are each provided with a hood 55 in the bottom of which is a drift opening 56 to permit cinders, dust, and elements to escape from these bearings.

The opening 57 in the side member of the frame in Figure 18 is adapted to receive a pin or other suitable device whereby the lumber door may be held in open position during loading.

The lower edge of the lowermost vane in Figure 18 is, when the vanes are in closed position in contact with the lumber door 80 46 whereby the door is securely locked in closed position by means of said vane in addition to the gravity latch 49.

The vanes of a car ventilator are subjected to shocks and strains incident to the shifting of the load in the car, and also the weaving of the car in service conditions, therefore, I prefer to make the vanes corrugated, or substantially in a compound curve in cross section, whereby they may have a maximum of strength to resist these shocks and strains.

The vanes are provided with flanges 58 on their longitudinal edges which flanges function to stiffen the vanes, and also function 95 as baffles to prevent cinders and the elements passing into the car. In the event of a heavy rain fall accompanied by a high wind rain would be driven between the vanes into the car, but with vanes having baffles 100 58, the rain strikes the curved face of the vane and is thereby deflected outwardly, and it will fall outside of the car. The baffle 58 will deflect outwardly and downwardly any rain that may seek to pass over 105 the upper edges of the vane. The lower edges of the vanes are also provided with stiffening ribs or flanges 59.

From the foregoing it will be seen that I have provided a ventilator which is easily 110 assembled, strong in construction and efficient in action; also that the ventilator is one which may be quickly and easily operated and so assembled that the blades may not be removed or the contents of the car 115 removed by access through the ventilator.

It is also to be understood that the embodiments of the ventilator shown are of a preferred form, but many slight changes might be made in the construction or the 120 details of construction, without in any way departing from the spirit and scope of the invention.

What I claim is:

1. In a car end having vertical braces 125 each comprising a web, a base flange, and a top flange, the top flange of each brace extending in opposite directions and toward

- the sides of the car, whereby drafts across the end of the car will be deflected by said top flanges, a ventilator secured to and between said pair of end braces and to the rear 5 of the vertical plane of the top flange of said braces whereby the ventilator is protected from side drafts.
2. In a car end the combination with vertically disposed end braces each having a web, 10 a top flange and a bottom flange, end sheets secured to the bottom flange of said braces, a ventilator frame, flanges extending from the sides of said frame and constructed to overlap the end sheets and be secured to the 15 base flange of said braces.
3. In a car end the combination with vertically disposed end braces each having a web, a top flange and a bottom flange, end sheets secured to the bottom flange of said braces, 20 a ventilator frame, flanges extending from the sides of said frame and constructed to overlap the end sheets and be secured to the base flange of said braces, the top flanges of said braces extending in opposite directions 25 and toward the sides of the car.
4. The combination with a car ventilator frame having top, bottom, and side members, and vanes pivotally mounted within the frame, one of said side members having a 30 slot the top of which registers substantially with the plane of the underface of one of the vanes when said vane is in open position, the other end of the slot substantially registering with the plane of the upper face of said 35 vane and in its closed position, a latch pivotally mounted on said side member and constructed to pass through said slot to hold the vanes in open or closed position, and means to lock said latch in its adjusted position.
- 40 5. In a car ventilator having vanes pivotally mounted therein, a slot in one side member of the frame, of a latch pivotally mounted on the outside of the side member having the slot, constructed to engage the underface of one of said vanes to lock the 45 vanes in open position and to engage the upper face of said vanes to lock the vanes in closed position, and means to lock said latch in its adjusted position.
- 50 6. In a car ventilator frame comprising top, bottom and side members, a hood projecting forwardly from the top member and an upstanding flange at the outer edge of the bottom member, outwardly extending 55 flanges on the said top, bottom, and side members constructed to be attached to car structure, vanes pivotally mounted in said frame, stops on the inner face of each side member disposed to break joint with each 60 other whereby a weatherproof joint is formed between the ends of the vanes and the sides of the frame, a screen disposed across the rear face of the frame, means cou-
- pling the vanes together for simultaneous operation, and a single latch to lock the 65 vanes in open and closed position.
7. The combination with a car ventilator frame having top, bottom, and side members, and vanes pivotally mounted within the frame, one of said side members having a 70 slot the top of which registers substantially with the plane of the underface of one of the vanes when said vane is in open position, the other end of the slot substantially registering with the plane of the upper face of said 75 vane in its closed position, a latch pivotally mounted on said side member and constructed to pass through said slot to hold the vanes in open or closed position.
8. In a car ventilator having vanes pivotally mounted therein, a slot in one side member of the frame, of a latch pivotally mounted on the outside of the side member having the slot, constructed to engage the underface of one of said vanes to lock the 85 vanes in open position and to engage the upper face of said vane to lock the vanes in closed position.
9. The combination with a car ventilator frame having top, bottom, and side members, 90 and vanes pivotally mounted within the frame, one of said side members having a slot the top of which registers substantially with the plane of the underface of one of the vanes when said vane is in open position, the 95 other end of the slot substantially registering with the plane of the upper face of said vane in its closed position, a latch mounted on said side member and constructed to pass through said slot to hold the vanes in open or 100 closed position, and means to lock said latch in its adjusted position.
10. The combination with a car frame having top, bottom, and side members, and vanes pivotally mounted within the frame, one of said side members having a slot the 105 top of which registers substantially with the plane of the under face of one of the vanes when said vane is in open position, the other end of the slot substantially registering with the plane of the upper face of said vane in 110 its closed position, a latch mounted on said side member and constructed to pass through said slot to hold the vanes in open or closed position.
11. In a car ventilator having vanes pivotally mounted therein, a slot in one side member of the frame, a latch operatively engaging said slot and constructed to engage the underface of one of said vanes to 115 lock the vanes in open position and to engage the upper face of said vane to lock the vanes in closed position.

In testimony whereof I affix my signature.

VINTON E. SISSON.
